UNITED STATES PATENT OFFICE.

LOUIS G. DALBY, OF BROOKLYN, NEW YORK.

DESIGN FOR DUST-PANS.

Specification forming part of Design No. **11,139**, dated April, 8 1879; application filed March 10, 1879.
[Term of patent 3½ years.]

To all whom it may concern:

Be it known that I, LOUIS G. DALBY, of Brooklyn, in the county of Kings and State of New York, have invented certain new and useful Improvements in Designs for Dust-Pans; and I do hereby declare that the following is a full, clear, and exact description of the invention, which will enable others skilled in the art to which it appertains to make and use the same, reference being had to the accompanying drawing and to the letters of reference marked thereon, which form a part of this specification.

The accompanying drawing fully illustrates my design.

The body of the dust-pan, composed of the bottom A, back B, and sides C C, is all struck up of one piece of sheet metal. The metal at the two rear corners forms a series of scallops or corrugations, *a a*, which add to its appearance. The bottom A is also provided with a series of corrugations, *b b*. These corrugations are divided into two groups curved outwardly from the center in opposite directions, to correspond with the curvature at the ends of the pan.

D is the handle, which is at its inner end made angular, to fit across the back B and under a part of the bottom A, it being united to said back and bottom.

F is an ornamental plate extending from the edge of the back B over a portion of the handle.

What I claim is—

1. The design for dust-pan herein shown and described, consisting of the bottom A, back B, sides C C, and scallops or corrugations *a a* at the corners, substantially as set forth.
2. The design for dust-pan, consisting of the bottom A, back B, sides C C, corner scallops or corrugations *a a* and the corrugations *b* in the bottom, arranged in two groups curving outwardly from the center in opposite directions, substantially as herein shown and described.
3. The design for dust-pan, consisting of the body A B C, having corner scallops *a* and bottom corrugations *b*, the angular handle D, and plate F, substantially as herein shown and described.

In testimony that I claim the foregoing as my own I have hereto affixed my signature in presence of two witnesses.

LOUIS G. DALBY.
